UNITED STATES PATENT OFFICE.

GUSTAV DUVINAGE, OF PASEWALK, GERMANY.

SLIDE-VALVE.

SPECIFICATION forming part of Letters Patent No. 440,349, dated November 11, 1890.

Application filed July 28, 1890. Serial No. 360,211. (No model.)

To all whom it may concern:

Be it known that I, GUSTAV DUVINAGE, engineer, of Pasewalk, in the Kingdom of Prussia and German Empire, have invented new and useful Improvements in Combined Slide-Valves and Distribution Slide-Valves, of which the following is a specification, reference being had therein to the accompanying drawings.

10 This invention relates to equilibrated slide-valves for steam-engines; and it has for its object to secure greater simplicity in construction, and an almost perfect and easily varied degree of equilibration.

15 The peculiarity of the slide-valve constructed according to these improvements consists in its being formed of a hollow piston-like body longitudinally slotted along its upper side, in which a cylindrical expansion-slide is arranged eccentrically, so as to enable the distribution of the steam to the main valve to be varied, as may be desired, by turning the expansion-slide, which is provided with angular ends.

20

25 I will more particularly describe my said invention, with reference to the accompanying drawings, in which—

Figure I shows a cross-section of a valve constructed according to these improvements; 30 Fig. II, a longitudinal vertical section of the same, and Fig. III a plan of the expansion-valve surface unrolled to a plane surface and of the main valve not unrolled.

The main slide A is constructed as a piston-like cylindrical body bored out eccentrically and provided with openings for the passage of the steam, and slides in the valve-chest, which is bored out cylindrically. It has formed in its upper side, opposite to the 35 steam-ports D F and the exhaust-port G, a longitudinal slot s, which gives to the main slide a certain degree of elasticity and serves to insure its fitting closely in its seating within the valve-chest. Through the slot s the steam 40 which enters the hollow part of the expansion-

slide B is caused to exert a certain pressure upon the main slide A, and thus to force it against the cylindrical bore of the steam-chest, and causes it to fit closely therein, preventing its being lifted without at the same 50 time causing any undue friction. The amount of the steam-pressure upon the surface of the slide may be regulated by the width of the slot.

The sliding surface of the expansion-valve 55 is formed to a curvature corresponding with the inner curvature of the main valve. The expansion-slide is arranged in an eccentric position relatively to the axis of the main valve, as shown in Figs. 1 and 2, and it is constructed with angular ends U V, as represented in Fig. 3, in a similar manner to the Rider valve. According to the angular position of this valve the steam will be cut off 60 earlier or later. The main valve and the expansion-valve are moved independently of each other by means of suitable rods.

By the hereinbefore-described arrangement the main valve is almost entirely equilibrated without the necessity for the use of any complicated mechanism. Moreover, short steam-passages are secured within the main valve, and the dimensions of the slides themselves 65 are considerably reduced.

What I claim, and desire to secure by Letters Patent of the United States, is—

The construction, combination, and arrangement of a cylindrical main valve bored eccentrically, provided with a longitudinal slot, and fitting within a cylindrical valve-chest, an expansion-valve having a transverse curvature to fit the bore of the main valve, and angular ends, substantially as described.

In witness whereof I have hereunto set my 85 hand in presence of two witnesses.

GUSTAV DUVINAGE.
